DIGGING MACHINE

Gwyn E. Russell, Riverside, Calif.

Application November 18, 1947, Serial No. 786,559

7 Claims. (Cl. 212—42)

1

The present invention relates to coin controlled dispensing apparatus of the crane type including a manually positionable bucket or claw in which the amount or character of the merchandise vended depends to some extent upon the skill of the operator.

An important object of the present invention is to provide improved dispensing apparatus of the type specified characterized by its simplicity of construction with a reduced number of elements arranged in a foolproof manner to require a minimum amount of maintenance.

Another object of the present invention is to provide improved apparatus of the type specified which may be simple and easily manufactured in large quantities with present day mass production methods and operations.

Still another object of the present invention is to provide improved operating mechanism in apparatus of the type specified, said apparatus being effective in a novel manner to move the bucket or claw from a normal, at rest, suspended position to a position above a desirable article after which the mechanism automatically allows the bucket to drop over such article with the bucket in open position and to thereafter cause the upward and horizontal movement of the bucket to a position above a dispensing chute after which the bucket is automatically opened and maintained in stationary position.

Another object of the present invention is to provide an improved mechanism of the type specified in which the operating mechanism is simple and of a minimum number of parts.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

Figure 1 is a sectional view through a portion of the apparatus embodying the present invention showing the crane bucket or "claw" in its normal at rest suspended position and corresponds substantially to a sectional view on the line 1—1 of Figure 4.

Figure 2 is a detail view similar to Figure 1 while it is being lowered from its raised position shown in Figure 1.

Figure 3 is a view similar to Figure 2 and shows the bucket in the closed position which it assumes when it is being raised upwardly.

Figure 4 is a sectional view of the machine

2

embodying the present invention taken substantially on the line 4—4 of Figure 1.

Figure 5 is a sectional view taken substantially on the line 5—5 of Figure 4.

Figure 6 is a view similar to that shown in Figure 5 taken substantially on the line 6—6 of Figure 4.

Figure 7 is an enlarged sectional view of a portion of the apparatus shown in Figure 1.

Figure 8 is a sectional view through the clutch arrangement taken substantially on the line 8—8 in Figure 6.

Figure 9 is a sectional view taken substantially on the line 9—9 of Figure 1 and shows a part of the coin operating mechanism.

Figures 10, 11 and 12 show progressively in that order the relative positions of the release mechanism when the manually operable member shown in Figure 9 is moved inwardly and then outwardly after the deposit of the proper coin in the slot.

Figure 13 is a view taken substantially in the direction indicated by the arrows 13—13 in Figure 4 and shows the manner in which one of the electrical switches is maintained in open position.

Figure 14 is a view similar to the view shown in Figure 13 but with the operating mechanism in a different position to allow closure of the switch.

Figure 15 is a view taken substantially in the direction indicated by the arrows 15—15 in Figure 17.

Figure 16 is a view similar to the view shown in Figure 15 but with the operating mechanism in different position to allow closure of the switch shown both in Figures 15 and 16, it being noted that Figures 13 and 15 correspond to positions of the switches shown therein while the apparatus is normally at rest and Figures 14 and 16 correspond to corresponding positions of the operating mechanism during a cycle of operation.

Figure 17 is a sectional view similar to the view shown in Figure 1 but with parts of the apparatus removed to more clearly show the release mechanism.

Figure 18 shows further constructional details of the clutch assembly shown in Figure 8 taken substantially on the line 18—18 of Figure 8.

Figure 19 shows the electrical circuit connections for energizing the driving motor.

Figure 20 is a view in side elevation of an improved bucket, in open position, embodying the present invention.

Figure 21 is a view looking up from the bottom

of the bucket shown in Figure 20 when the bucket is closed.

Figure 22 is a sectional view taken in the direction indicated by line 22-22 in Figure 21 when the bucket is open.

Figure 23 is a view taken substantially in the direction indicated by the arrows 23-23 in Figure 20.

Figure 24 is an enlarged view of a portion of the bucket shown in Figure 20.

The present invention is shown embodied in a well known type of crane coin controlled machine from which the quality and quantity of articles dispensed depends to some degree on the skill of the operator. Such machines are usually coin operated. Upon proper insertion of a coin the mechanism is free to be operated by an individual who may move the bucket to a seemingly advantageous position. Upon manual movement of the bucket, an electrically driven mechanism is automatically energized to initially render the manual control inoperative and then to move the bucket through a cycle of operations. Such cycle of operations includes lowering and closing of the bucket, raising the bucket while it is closed, and then moving the bucket laterally and vertically to a position over an article dispensing chute wherein the bucket is caused to open to allow any articles carried therein to drop into the discharge chute.

The operation is effected in the present arrangement upon placing a coin in a conventional coin chute 10 and then moving the manually operable slide 11 of conventional structure first inwardly and then outwardly to cause such coin to drop into a coin box (not shown). This coin operated mechanism may be of conventional structure with the reciprocal slide member 11 thereof attached to an actuating member 14 arranged to operate a mechanism to allow the bucket 15 to be positioned upon subsequent turning of the manually rotatable knob 16. While the knob 16 is being turned, a switch 17 is caused to close to thereby energize the bucket moving mechanism which is driven by the electrical motor 18.

The mechanism driven by motor 18 includes a pair of eccentrically mounted arms 20, 21 which are attached through flexible bead cables 22, 23 respectively to the bucket 15 after passing over pulleys 24, 25 on the cab structure 26 and boom structure 27, respectively. The boom structure 27 pivotally mounted on the cab structure 26 at 28 is held in adjusted position by the flexible bead cable 30 having one of its ends anchored onto the cab structure 26 and the other one of its ends anchored to the free end of the boom 27.

The bucket 15 may be of conventional construction. The bucket 15 may, for example, and not as a limitation, be of the type shown and described in the Bartlett Patent 2,166,854, and as shown therein, the cables 22, 23 may be attached thereto for producing opening and closing movement of the bucket jaws. This bucket 15 may likewise be of the construction shown in Figures 20-24, inclusive.

The cab 26 with the bucket 15 mounted thereon is mounted on the rotatable shaft 35 about a vertical axis for positioning and moving the bucket mounted thereon. This shaft 35 projects through a partition 36 and through a stationary frame-work 36A, and is journaled at vertically spaced points 37, 38. The cab is initially moved outwardly from its normal, at rest, position shown in Figure 1 by turning the manual control

knob 16 which is initially coupled to the shaft 35 through the clutch 40, the shaft 41, the universal joint 42, shaft 43, and the releasable friction clutch element 44 arranged to frictionally engage the underside of the disc 45 which is keyed on the shaft 35. After a predetermined amount of movement of the control knob 16, the projection 46 (Figures 15 and 16) on the upper face of the disc 45 causes the switch 17 to close to thereby energize the motor 18 and a short time thereafter the cab shaft 35 is driven by the electrical motor 18 through the mutilated gear 49 keyed to the shaft 35, the coupling between the mutilated gear 48 and the motor 18 comprises in order, as shown in Figures 5 and 13: motor shaft 50, flexible coupling 51, shaft 52, worm gear 53, shaft 54, coupling 55, shaft 56, worm gear 57, shaft 58 and mutilated gear 59 keyed on shaft 58 for cooperation with the mutilated gear 48 on the cab shaft 35. It is noted at this point that the manual control knob 16 serves to move the bucket 15 to its most extreme position away from its normal, at rest, position shown in Figure 1 while the motor 18 which is automatically energized by operation of knob 16 serves to move the bucket back to normal position.

Upon energization of the motor 18 produced by manual operation of knob 16, the shaft 58 is driven to allow closure of switch 60 which is normally maintained in open position by the projection 61 on the mutilated gear 59 engaging the arm 62 of switch 60 and thereafter the teeth on the mutilated gear 59 which are normally out of engagement with the teeth on mutilated gear 48, engage the teeth on the other cooperating mutilated gear 48 to rotate the cab structure 26 in a direction of rotation opposite that produced by the knob 16.

An important feature of the present invention is the manner in which the bucket is raised and lowered and opened and closed. This mechanism includes a pair of eccentrically mounted arms 20, 21 affixed to the outer ring 70 of a ball-bearing member 71, the inner ring member 72 of which has its plane at an acute angle with respect to the axis of the vertical shaft 58 and has a disc member 74 press-fitted therein. This disc member 74 has a circular aperture therethrough angularly related to the axis of the member 74 for receiving the shaft 58 to which it is keyed by set screw 75. The arms 20, 21 extend in parallel directions and are affixed at adjacent ends, on the one hand, to diametrically opposite points on the outer ring member 70 and, on the other hand, to corresponding ends of the flexible bead-type cable 22, 23.

It is apparent that upon rotation of the shaft 58 produced by the motor 18, the outer bearing ring 70 undergoes a nutating motion, i. e., the ring not only has a rotational component but a rectilinear component as well. The arms 20, 21 attached at diametrically opposite points on the ring 70 are at such length that the desired bucket opening, closing, raising and lowering motions are produced.

The plane of the bearing member 71 may be at an angle of approximately thirty-five degrees (35°) with respect to the axis of shaft 58.

Cable 22 serves essentially to open and to maintain bucket 15 open while cable 23 serves essentially to close and to maintain bucket 15 closed. When cables 22 and 23 are moved simultaneously in the same direction, the bucket is raised or lowered as the case may be; but when cable 22 moves relative to cable 23 or vice versa

there is a bucket opening or closing operation as the case may be. When the bucket is initially moved by knob 16, it remains open since the shaft 58 is not rotated, but upon subsequent rotation of shaft 58, the arms 20, 21 are both moved upwardly at substantially the same rate until the bucket 15 reaches its lowermost position. Then upon further rotation of shaft 58, cable 23, attached to arm 21, is moved relative to cable 22 to cause the bucket to close after which both cables 22, 23 or arms 20, 21 are moved downwardly at substantially the same rate of speed to raise the bucket in its closed position. In other words, when the bucket is being swung from its normal position and then lowered, the cable 22 supports the greater weight of the bucket to maintain it open; and upon the subsequent upward movement of the bucket and its return pivotal movement to a point near its at rest position above the discharge chute (not shown), the cable 23 supports the greater weight of the bucket to maintain it closed.

In order to assure such motion of the arms 20, 21 and attached cables 22, 23, the arm 20 is confined to move only in a vertical direction between the two-spaced vertical stationary guide members 80, 81.

It is noted that the shaft 58 makes one revolution per cycle to return the arms 20, 21 to their original position and for that reason the shaft 30 is termed a "one revolution shaft".

The friction clutch element 44 is normally maintained out of driving engagement with the disc 45 by the catch mechanism 85 (Figures 10-12, 17) arranged to cooperate with the pivoted arm 86. In the absence of the catch 85, the arm 86 which is pivoted on the frame 36A presses the clutch element 44 into engagement with the disc 45 due to the action of the tension spring 87 having one end affixed to frame 36A and the other one of its ends affixed to arm 86. Normally, as shown in Figure 10, the catch 85 maintains the free end of the lever member 86 in depressed position. Upon depositing a coin and the subsequent manual inward and outward movement of the slide member 11 with the actuating member 14 attached thereto, the catch member 85 is unlatched as indicated in the series of Figures 10 through 12, inclusive. It is noted that the catch member 85 is pivoted on the frame 36A and is provided with an arm 88 which is attached to an end of a tension spring 89, the other end of which is attached to the frame 36A. The catch member is normally biased into engagement with the lever member 86 by the tension spring 89. Upon inward movement of the slide actuated member 11, 14 and push rod 90 attached thereto, the catch member 88, as shown in Figure 11, is deflected out of catch engaging position by the rod 90 and blocks upward movement of the lever member 86. Therefore, it is necessary that the reciprocal slide actuating member 11 be moved to its normal position to allow the spring biased lever member 86 to raise, which event occurs as indicated in Figure 12 when the slide actuating member is withdrawn. Thus, in Figure 12 the lever member 86 is allowed to raise to establish the driving connection between knob 16 and the disc 45.

After a cycle of operation is approximately half completed, the lever member 86 is depressed by means described presently to allow the catch 85 to automatically lock it as indicated in Figure 10. The particular means for depressing the lever member 86 comprises an extension 21A from

the eccentrically mounted bearing ring member 70. This event occurs as indicated in Figure 3 when the bucket is being raised to its raised position.

5 The one-way clutch 40 shown in detail in Figures 8 and 18 is of conventional structure and serves to couple the manual control knob 16 to the shaft 41 in such a manner that the shaft 41 may be rotated only in that direction indicated 10 by the arrow 100 in Figure 16.

The shaft 41 is connected to the cylindrical housing 40A by the set screw 101 while the shaft 102, upon which the control knob 16 is keyed, is connected to the inner cylindrical member 15 40B of the clutch 40 by the set screw 104. In conventional manner, the three rollers 105 disposed in the triangular shaped peripheral openings in the cylindrical member 40B are moved into locking engagement with the internal wall 20 of the cylindrical housing 40A only when the shaft 102 is moved in the direction indicated by the arrow 107 in Figure 8. Thus, the control knob 16 with the interposed clutch 40 serves to move the boom structure 27 in one direction only: 25 namely, to the left as indicated by the arrow 109 in Figure 4.

The amount of movement of the boom structure 27 in a circular orbit produced by rotation of the knob 16 depends upon the speed at 30 which the knob 16 is rotated for the reason that the mechanical drive incorporating the control knob 16 is automatically made inoperative as explained previously when the bucket reaches its lowermost position. In other words, the time 35 during which switch 60 remains closed is of a substantially constant predetermined time during which, and only during which, the control knob 16 is effective for manual positioning of the boom 27 and bucket 15. Thus it is clear that 40 an operator of the machine has only a limited amount of time within which to position the bucket 15 vertically above the desired article but within such limited time he may control the position of the bucket. In this respect it is noted 45 that the operator has manual control of the bucket 15 until the arm extension 21A moves downwardly to engage the lever member 86 as indicated in Figure 3.

Another important feature of the present invention is the provision of the two mutilated gears 48 and 59 keyed respectively on shafts 35 and 58. It is noted that in the normal, at rest, position of the bucket 15, these two mutilated gears are out of engagement as shown in Figure 13. It is further noted that the teeth on gear 48 extend substantially an arcuate distance of 180° while the corresponding cooperating teeth on gear 59 extend only an arcuate distance of 90°. The gear 59, of course, makes but one complete revolution per cycle and travels an arcuate distance less than 270° before engaging the teeth on gear 48, the exact angular distance depending upon the amount the gear 48 is originally displaced from its normal, at rest, position by operation of the manual control knob 16.

The two switches 60 and 17 are both of the same type in that each has a spring contact member normally held out of circuit closing position by a corresponding pin or projection 61 and 46 respectively on gear 59 and disc 45. These two switches, as indicated in Figure 19, are connected in parallel or shunt to one another and in series with the windings of motor 18 so that 70 closure of either one of the switches 17 or 60 re-

sults in current flow to the motor 18 from the supply terminals 112 and 113.

The operation of the machine is briefly as follows: An operator deposits a suitable coin in the conventional type of coin chute 10 and then moves the coin slide 11 first inwardly and then outwardly. Such inward and outward movement of the coin slide 11 with the member 90 attached thereto results in unlatching the lever member 86 in the series of operations indicated in Figures 17, 10, 11 and 12. When the lever member 86 is thus unlatched a driving connection incorporating the movable clutch element 44 is provided between the control knob 16 and the disc 45 so that the operator, upon rotation of the knob 16, may move the shaft 35 with the connected boom 27 and bucket 15 to a desired position. Upon such movement of the shaft 35 and the disc 45 keyed thereon, the switch 17 is allowed to close to thereby energize the driving motor 18. Upon such energization of the motor 18 the shaft 58 coupled thereto is rotated together with the mutilated gear 59. Upon movement of such gear 59 the switch 60 is allowed to close, thereby assuring energization of the motor 18 during the remainder of the cycle. Also, when the shaft 58 is thus rotated by the motor 18 the arms 20 and 21 are moved in such a manner that the bucket 15 is, in turn, lowered, closed and then raised while closed in accordance with forces imparted to the flexible cables 22 and 23 on the ends of the arms 20 and 21, respectively. When the arm 21 is thus moved to its uppermost position shown in Figure 3, the extension 21A thereon engages and presses the lever member 86 to restore it to its latched position indicated in Figure 10, to condition the apparatus for another subsequent cycle of operations initiated by depositing another coin. As the mutilated gear 59 on the one revolving shaft 58 continues to rotate, it engages the teeth on the gear 48 to return the bucket 15 to its at rest position wherein the bucket is automatically opened by the forces imparted to cables 22 and 23 to discharge the contents of the bucket into a discharge chute. At the end of travel of the gear 59, projection 61 causes the switch 60 to open to thereby completely deenergize the motor 18.

The bucket 15 may be constructed as shown in Figures 20 through 24, inclusive, wherein the bucket has a pair of jaws 115 and 116 with side walls 117 and 118, respectively. The upper ends of the said side walls extend inwardly and terminate in ears 120. The ears on one jaw are offset inwardly with respect to one another and overlap the ears of the other jaw to provide uniplanar external faces or walls on both jaws. The ears 120 are provided with openings through which a pivotal bolt or pin 125 extends. Bucket jaw 116 is slotted at 126 within which a spring member 127 is deposited to press the bolt or pin 125 in one of a series of curved sections 129 of the slot 126, to thereby maintain the jaws 115 and 116 in adjusted position for a purpose described later. For this purpose it is noted that the spring 127 is of the leaf or cantilever type and has one of its ends affixed to the jaw 116 and the other one of its ends arranged to engage the body of the pin 125 to press it into one of the curved sections 129 of the slot 126.

The lower ends of the bucket jaws 115 and 116 terminate in perforate extensions 135 and 136, respectively, between which a digit 137 is adjustably mounted in position by frictional

forces. As the digits 137 consist of a tooth bar having teeth thereon arranged to intermesh with corresponding teeth on the other bar, these digits 137 are frictionally held on the bucket jaws 115 and 116 by pins 138 passing through such jaws and through such digits. Each of the digits 137 is susceptible to adjustment to any degree of angularity, thereby providing bucket jaws of adjustable grasping power. These digits 137 may be conveniently adjusted to decrease their grasping power by squeezing the two bucket jaws 115 and 116 together. Upon such squeezing of the two bucket jaws 115 and 116, the digits 137 revolve to adjusted position about the pivot pins 138 upon which they are maintained in position by frictional forces between the pin 138 and the digits. Further, each bucket jaw has a weighted member 140 held in adjusted position thereon by the set screw 141 engaging the walls defining the slotted portions 145. The position of these weights 140, which may be of lead, also influences the gripping power of the bucket jaws.

The bucket 15 is attached to the apparatus shown in the previous figures by attaching a link 23A to the pin 125 and cable 23 and by connecting the cables 22 to the bucket jaws 115 and 116 by means of links 22A. The cables 22 serve to support the bucket and to maintain the bucket jaws in bucket opening position while the cable 23 when stressed serves to move the pin 125 upwardly to close the bucket.

It is evident that the gripping power of the bucket shown in Figures 20 through 24 inclusive may be adjusted in three different ways; namely:

1. By adjusting the angular position of the digits 137 on their supporting pins 138;
2. By adjustment of the position of the weight 140; and
3. By adjustment of the pin 125 in the slotted portion 126 of the bucket jaw 116.

Thus, for example, the gripping power of the bucket may be increased by pivoting the digits 137 inwardly in the direction indicated by the arrows 150, by moving the weights 140 downwardly in the direction indicated by the arrows 151, and the gripping power of the bucket jaws may be decreased by moving the pin 125 in the slot 126 in the direction indicated by the arrow 152. As explained previously, the gripping power of the bucket may be conveniently decreased by squeezing the two bucket jaws 115 and 116 together. Depending upon where the squeezing pressure is applied, the digits 137 may be moved outwardly or the pin 125 may be moved in the direction indicated by the arrow 152 in the slot 126. It is apparent that these two adjustments may be made simultaneous; namely, adjustment of the digits 137 and adjustment of the pin 125.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. In a machine of the character specified, a bucket having two relative movable parts whereby the bucket may be opened or closed; a bucket hoisting chain therefor and a bucket closing chain therefor; a boom member supporting said bucket; a rotatable cab supporting said boom; a rotatable drive shaft; a roller bearing member

having an inner race and an outer race, the outer race being mounted eccentrically on said shaft, the outer race of said bearing member having a pair of projections thereon, one of said projections being attached to said bucket hoisting chain and the other one of said projections being attached to said bucket closing chain.

2. A vending machine of the character described, including an upstanding rotatably mounted shaft; a roller bearing member having an inner race and an outer race, the inner race being mounted eccentrically on said shaft; a cabin fixed on the top of said shaft with a crane mounted thereon; cables trained through said crane, one end of each of which passes through the cabin and is attached to the outer race of said roller bearing member; a shovel carried by the opposite ends of the cables; and a motor operatively connected to said shaft.

3. A vending machine of the character described embodying a motor-operated digging and hoisting mechanism which includes a crane with a pair of cables trained therethrough; a rotatable shaft; a roller bearing member having an inner race and an outer race, the inner race being mounted eccentrically on said shaft; one end of each cable engaging the digging part of said mechanism; and arms mounted on the outer race of said roller bearing member, each of said arms being engaged with one of the cables and movable by the motor through a vertical arc to exert a stress on its cable as the arm is moved by said mechanism.

4. A vending machine of the type specified including a digging and hoisting mechanism; means arranged to engage the digging and hoisting mechanism to raise and lower the digger of the latter; a motor in operative connection with the digging and hoisting mechanism to raise and lower the same; an electric circuit including said motor and digging and hoisting mechanism; a normally open switch in said circuit; and manually operated means engaged with said mechanism for moving the latter in a horizontal arc and to simultaneously close said switch.

5. A vending machine of the character described including a digging and hoisting mechanism with a rotatable shaft; manually operated means in operative connection with said mecha-

nism to urge the latter into a predetermined position preparatory to beginning the digging operation; a disc mounted on said means and movable therewith; a ball bearing member eccentrically mounted on said shaft with the outer member thereof having a pair of arms attached thereto; motive means including said arms in operative connection with the digging and hoisting mechanism for raising and lowering the bucket thereof; and means operated upon movement of said disc by said manually operated means to rotate the digging and hoisting mechanism independently of the manually operated means for urging said mechanism into position for dispensing the materials intercepted in the digging operation.

6. In a vending machine of the character described, a one revolution shaft; a ball bearing member on said shaft having an inner and an outer member with the plane thereof at an acute angle with respect to the axis of said shaft; a pair of arms on said outer member; means guiding one of said arms in a vertical line upon rotation of said shaft; a bucket member; and flexible cable means connected between said arms and said bucket to raise, lower, open and close the same in one revolution of said shaft.

7. In a vending machine of the character described including a supporting structure for a bucket, a first rotatable shaft arranged to move said supporting structure; a second rotatable shaft; flexible cable means movable with said second shaft arranged to hoist, lower, open and close said bucket; and an intermittent drive between said first and second shafts comprising at least one mutilated gear.
